PIPE COATING APPARATUS

Albert G. Perkins, Warsaw, N. Y.

Application November 26, 1934, Serial No. 754,792

10 Claims.

(Cl. 25—38)

This invention relates to certain new and useful improvements in pipe-coating apparatus of the type designed for applying a protective coating or lining to the inner walls of steel pipe lines.

5 One of its objects is the provision of a reliable and efficient apparatus of this character which is designed to travel through the pipe line and as it does so automatically applies an even and durable coating of plastic material onto the pipe wall by centrifugal force and at the same time trowels the coating so applied.

Another object of the invention is to provide a conveying means for the material which is so designed and constructed as to effectually and automatically release the head pressure on the material when it reaches a predetermined point to thereby provide for a constant and uniform feed of the material to the discharge end of the apparatus.

20 Another object of the invention is the provision of simple and effective means for troweling the material after it has been deposited on the pipe wall and to so mount the troweling means that it is self-aligning and self-adjustable to the surface of the applied coating material.

A still further object is to provide means for readily gaging at a glance the approximate thickness of the coating material as it is applied to the pipe wall.

25 Other features of the invention reside in the construction and arrangement of parts herein-after described and particularly pointed out in the appended claims.

In the accompanying drawings:—

30 Figure 1 is a side elevation of my improved coating apparatus, the same being shown within a pipe line for treating the interior wall thereof with a protective coating. Figure 2 is a rear end view of the apparatus arranged within the pipe. 40 Figure 3 is a front end view of the same likewise arranged within the pipe. Figure 4 is an end view, partly in section, of the means for supporting the trowel. Figure 5 is a top plan view of the feed hopper and the conveyor screw. Figure 6 is a longitudinal section taken in the plane of line 6—6, Figure 5. Figure 7 is a cross section taken in the plane of line 7—7, Figure 5.

Similar characters of reference indicate corresponding parts throughout the several views.

50 While my apparatus may be employed for coating different kinds of work, it has been primarily designed for treating the inner walls of steel pipe lines with a protective coating, such for example as a plastic-like material as concrete.

55 To this end the apparatus consists generally of

a carriage which is adapted to be propelled through the pipe line and which carries the working parts of the coating apparatus, such working parts comprising essentially a hopper for the coating material having a conduit or cylindrical feed chamber connected therewith; means for conveying the material from the hopper and through the conduit; a dispensing or discharge head into which the material is delivered from the conduit and from which it is discharged by centrifugal force onto the pipe wall; means for troweling the material after it has been applied to the pipe wall; and indicating means for gaging the thickness of the coating as it is applied to the pipe wall.

10 Referring now to the drawings, 10 indicates a section of the steel pipe line through which my apparatus is designed to travel for coating the inner wall thereof with a plastic coating of concrete or like semi-solid material. The carriage 20 of the apparatus, which carries its working parts, may be of any appropriate construction, that shown in the drawings, by way of example, consisting of a structural steel frame 11 provided at one end with traction or supporting wheels 12 and at its opposite end with a steering or caster wheel 13. Motion is transmitted to the traction wheels from an electric motor 14 through the medium of a chain drive 15 to a countershaft 16 and thence by gearing 17 to the axle of the traction wheels, a suitable speed-reducing transmission 18 being interposed between the motor and the chain drive for the purpose of propelling the carriage through the pipe at different speeds and thereby govern the thickness of the coating material applied to the pipe wall.

15 Mounted on the carriage frame 11 is a feed hopper or container 19 for the coating material, and communicating with this hopper is a feed conduit or chamber 20 which is disposed lengthwise and centrally of the machine and approximately axially of the pipe. Extending through this hopper and its communicating conduit is a tubular shaft 21 having a screw-conveyor 22 applied thereto which forces the material through 25 the hopper and its communicating conduit 20. This screw conveyor shaft may be driven from the electric motor 14 by suitable speed reducing gearing 23. At its discharge end the feed conduit has a revolvable dispensing head 24 which 30 directs the material by centrifugal force onto the pipe wall. This dispensing head may be rotated from the motor 14 through the medium of a belt and pulley 25, as shown in Figure 1.

35 In order to deliver the material to the dis-

pensing head at a constant and uniform rate, that portion of the feed screw 22 disposed within the hopper 19 is so designed and constructed as to automatically release the head pressure on the material when it reaches a predetermined point. To this end, the hopper-engaging portion of the conveyor screw is composed of approximately spiral shaped flexible portions or blades 26 which are secured at one end to arms 27 radiating from the shaft 21, while their opposite ends are free to permit the blades to flex in a direction axially of the shaft and thereby release the pressure imparted to the material by the screw. These flexible blades together form a disconnected screw-section and while they normally effect the proper feed of the material from the hopper to the conduit 28, they effectually prevent any over-head pressure being imparted to the material, with the result that the material is delivered at a constant rate to the dispensing head 24. The bottom wall 28 of the hopper 19 preferably extends upwardly to meet the bottom of the conduit 28, as shown in Figure 6, and extending from the top side of the inlet end of said conduit in opposing relation to the inclined bottom wall of the hopper is an oppositely-inclined wall 29. By this construction, the material in the hopper is properly directed to the conduit 28.

The troweling mechanism for smoothing down the coating material after it has been applied to the pipe wall preferably consists of a plurality of retractile trowels 30 which are so mounted as to revolve at a comparatively slow speed over the coated wall and to be automatically self-aligning to the coated surface. Each of these trowels is connected to a vertically-swinging lever or rod 31 pivoted to a revolving radial arm 32 and free to turn about its longitudinal axis in a swivel fitting 33 pivoted to said arm, the swivel fitting or block forming a fulcrum about which the trowel-lever swings. For the purpose of adjusting the trowel-carrying levers to accommodate pipes of varying diameters, the arms 32 may be provided with a series of openings 34 for receiving the corresponding pivot blocks 33 of said levers. Each trowel-carrying lever 31 is constantly urged in a direction to bring its trowel 30 into yielding engagement with the pipe wall by a spring 35 whose free end is coupled with the opposing end of the trowel-carrying lever by a swivel fitting 36. Any suitable means may be employed for shifting the trowels into and out of engagement with the pipe wall. For example, the trowel-carrying lever may be connected by a link 37 with the arm 38 of a rock member 39 which is actuated in one direction or the other by a conical drum 40 to accordingly shift the trowel-carrying lever toward and from the pipe wall. The link 37 is likewise connected by a swivel fitting 41 to the trowel-carrying lever 31. The specific means for actuating the conical drum forms no part of the present invention and a detailed description thereof is therefore not deemed necessary.

By mounting the trowel-levers 31 in this manner, they are free to adjust themselves to the surface of the pipe coating and are adapted to swivel in their supporting fittings 33 without interfering with the spring and link connections 35 and 37, respectively.

70 For the purpose of gaging the thickness of the material as it is being applied to the pipe wall, I provide a suitable indicator which is preferably in the form of an adjustable bar 42 pivoted at 43 to the revolving trowel-carrying arm 32 or 75 like part and so disposed as to have its free end

in cooperative relation with a part borne by said arm, such for example as one of the trowel-carrying levers 31, as shown in Figure 4. The pivot 43 is of a character to frictionally hold the indicator bar in an adjusted set position. In using 5 this thickness gage, the operator sets the indicator bar 42 in abutting engagement with the adjoining portion of the trowel-carrying lever 31, this adjustment being made before the material is applied to the pipe wall. As the material is 10 applied to the pipe wall and the trowels 30 smooth down the material, the latter are gradually shifted away from the pipe wall in accordance with the thickness of the coating material applied thereto, whereby a resulting space or gap will result between the indicator bar and the adjoining trowel-carrying lever, such space indicating or corresponding to the thickness of the material applied 15 to the pipe wall.

Disposed rearwardly of the trowels to revolve 20 about the same axis is a spray gun 44 for delivering a curing fluid onto the coated pipe-wall.

I claim as my invention:—

1. In an apparatus of the character described, a rotatable member, a swivel-mounted lever pivoted to said member to swing substantially in the plane thereof, a trowel applied to said lever, and means connected to said lever to swing the same and its trowel radially inward and outward, said means including swivel connections to said 30 lever.

2. The combination with a pipe-coating machine having means for applying a lining to the pipe-wall, of a means engageable with the lining after it is applied, and an indicator disposed in cooperative relation to said lining-engaging means for gaging the thickness of the lining applied to the pipe-wall.

3. The combination with a pipe-coating machine having means for applying a lining to the pipe-wall, of a means engageable with the lining after it is applied, and an adjustable indicator member disposed in cooperative relation to said lining-engaging means for gaging the thickness of the lining applied to the pipe-wall, said indicator member being initially set in accordance with the position of the lining-engaging means before the application of the lining to the pipe-wall, whereby, after the lining is applied, the distance between said means and the indicator member represents the thickness of the lining applied 45

4. In a pipe-coating apparatus of the character described, a rotatable member, a trowel-bearing lever pivoted to said member to swing in a direction to bring the trowel toward and from the pipe-wall, and an indicator mounted on said member in cooperative relation to said lever for gaging the thickness of the coating applied to the pipe-wall.

5. In a pipe-coating apparatus of the character described, a rotatable member, a trowel-bearing lever pivoted to said member to swing in a direction to bring the trowel toward and from the pipe-wall, and an adjustable indicator fulcrumed at one end to said rotatable member and 65 cooperating at its opposite end with said trowel-bearing lever to gage the thickness of the coating applied to the pipe-wall.

6. An apparatus of the character described, comprising a hopper terminating at its discharge end in a feed conduit, and a feed screw arranged in said hopper and extending through its feed conduit, that portion of the feed screw located in the hopper including disconnected spiral blade-sections flexible axially of the screw to re- 70 75

lease the pressure on the material and the remaining portion of the screw being continuous to provide for a constant and uniform feed of the material through the feed conduit.

5 7. An apparatus of the character described, comprising a hopper having a straight portion and a conical portion terminating at its discharge end in a conduit, and a feed screw arranged in said hopper and extending through its feed conduit, that part of the feed screw located in the straight portion of the hopper being composed of disconnected spiral blade sections flexible in the direction of the screw axis, and the remaining portion of the screw being continuous.

10 8. An apparatus for coating pipe walls and the like, comprising a feed conduit adapted for communication with a source of coating material, means disposed at the discharge end of said conduit for delivering the material onto the pipe-wall, a revolving trowel disposed rearwardly of said material-delivering means for smoothing down the material after it has been deposited on the pipe-wall, means for universally mounting said trowel to render it self-adjustable and self-aligning to the pipe wall, and means disposed rearwardly beyond and revolvable with said

trowel for delivering a curing fluid onto the coated pipe-wall, said material-delivering means, said trowel, and said fluid-delivering means being all revolvable about a common axis coincident with the feed conduit.

15 9. A troweling device for use in the coating treatment of pipe-walls and the like, a revolving support, a trowel applied thereto and having a smooth working face, and means for universally mounting said trowel on said support to render it self-adjustable and self-aligning to the feed conduit.

10 10. A troweling device for use in the coating treatment of pipe-walls and the like, comprising a revolving arm having a retractable trowel applied thereto for smoothing down the material after it has been applied to the pipe-wall, a trowel-carrying lever pivoted to said arm to bring the trowel toward and from the pipe-wall, an actuating member for shifting said trowel-carrying lever to a retracted position, a spring for urging said lever in the opposite direction, and swivel connections between the lever and the adjoining connecting ends of said actuating member and said spring, whereby the trowel is rendered self-aligning to the pipe-wall.

lease the pressure on the material and the remaining portion of the screw being continuous to provide for a constant and uniform feed of the material through the feed conduit.

5 7. An apparatus of the character described, comprising a hopper having a straight portion and a conical portion terminating at its discharge end in a conduit, and a feed screw arranged in said hopper and extending through its feed conduit, that part of the feed screw located in the straight portion of the hopper being composed of disconnected spiral blade sections flexible in the direction of the screw axis, and the remaining portion of the screw being continuous.

10 8. An apparatus for coating pipe walls and the like, comprising a feed conduit adapted for communication with a source of coating material, means disposed at the discharge end of said conduit for delivering the material onto the pipe-wall, a revolving trowel disposed rearwardly of said material-delivering means for smoothing down the material after it has been deposited on the pipe-wall, means for universally mounting said trowel to render it self-adjustable and self-aligning to the pipe wall, and means disposed rearwardly beyond and revolvable with said

trowel for delivering a curing fluid onto the coated pipe-wall, said material-delivering means, said trowel, and said fluid-delivering means being all revolvable about a common axis coincident with the feed conduit.

15 9. A troweling device for use in the coating treatment of pipe-walls and the like, a revolving support, a trowel applied thereto and having a smooth working face, and means for universally mounting said trowel on said support to render it self-adjustable and self-aligning to the feed conduit.

10 10. A troweling device for use in the coating treatment of pipe-walls and the like, comprising a revolving arm having a retractable trowel applied thereto for smoothing down the material after it has been applied to the pipe-wall, a trowel-carrying lever pivoted to said arm to bring the trowel toward and from the pipe-wall, an actuating member for shifting said trowel-carrying lever to a retracted position, a spring for urging said lever in the opposite direction, and swivel connections between the lever and the adjoining connecting ends of said actuating member and said spring, whereby the trowel is rendered self-aligning to the pipe-wall.
